ASH DISCHARGER

Max Schwabach, London, England

Application September 1, 1933, Serial No. 687,895
In Germany September 7, 1932

9 Claims. (Cl. 110—165)

This invention relates to a device intended especially for the removal of ashes and other materials, for instance coke, also slag, from furnaces and the like. The present improved device 5 pertains to that type of such devices in which the respective material is led by means of a vertical tube or branch into a receptacle or trough containing water, said tube or branch extending down to below the level of the water so that it 10 is tightly closed by the same. The object of the present improvements is to simplify the device and to render its manipulation particularly convenient. This is obtained by arranging and supporting the water-filled receptacle or trough in 15 such a manner that it is horizontally shiftable and at the same time tiltable on an axis extending through the center of gravity of the receptacle or trough, the arrangement being such that the trough while being moved in that twofold manner does not in the least interfere with the above- 20 mentioned tube or branch through which the ashes or other material is introduced into the trough, or into the water of the same respectively. Owing to the tilting axle passing through the 25 center of gravity of the trough, as already stated, the tilting can be easily effected by hand.

The invention is illustrated diagrammatically and by way of example on the accompanying drawings on which Figure 1 is a longitudinal vertical section through an ash-removing device 30 designed according to this invention, Figure 2 is a transverse section through the same in the plane II—II of Figure 1, and Figures 3, 4 and 5 show three positions of the trough while it is 35 being tilted.

On the drawings, 1 denotes a vertical branch through which the ashes or other material enters into the trough 2 which contains water to the 40 level of the outlet 3 which serves as an overflow aperture. The branch 1 terminates below the level of the water so that it is closed air-tight and gas-tight by the same. 4 are running rolls which are attached to the trough at the two sides of the same adjacent to an axis extending through 45 the center of gravity of the trough, and said rolls can run on horizontal rails 5 forming, in the example shown, the lower portions of a stationary frame 5'. From this frame extend downwardly oscillable rods 7 which are connected 50 with one another at their lower ends by an axle 6 supporting the trough 2 by means of feet 12. The trough is, thus, supported by these feet, as well as by the rolls 4. I wish it, however, to be understood that the members 7, 6 and 12 may be 55 also differently arranged, but their arrangement

must at any rate be such that the trough is securely held in the position shown in Fig. 1 during the service hours.

The rod 6 serves also as a grip when the filled trough is to be emptied. This is effected by pulling the trough forcibly to the left (Fig. 1), the rolls 4 running then along upon the rails 5 until they arrive in the position 4' indicated by dotted lines in Fig. 1. Owing to the just described movements and, besides, owing to the trough also 10 being supported and guided by the rods 7, the trough and the other movable members assume finally the position denoted by the reference numerals 2', 4', 6' and 7' and indicated by dotted lines in Fig. 1. While the trough is being moved 15 from its operative position into its emptying position it assumes also the intermediate positions shown in Figs. 3-5, but in none of these positions is there interference with the branch 1. The oblique wall of the trough which normally 20 extends upwardly, as shown in full lines in Fig. 1, is finally downwardly directed, as shown in dotted lines in Fig. 1, and the entire contents of the trough will now slide down into a cart or truck 10.

As it can occur that the trough, prior to the 25 tilting, is not completely filled with ashes or whatever other material it may be so that a corresponding amount of water has remained in the trough, a small intercepting trough 9 is provided near the upper end of the oblique wall of the 30 main trough 2, the arrangement of the trough 9 relatively to the trough 2 being such that when this latter is tilted only a little, the water contained in it over the smothered ashes flows away into the small trough 9 and then the large trough 35 2 finally reaches a position in which the ashes etc. slide down into the truck. While the trough 2 is thus being moved, its discharge edge moves along the path indicated by the dotted line x—x' (Fig. 3), from which it is evident that the two 40 troughs never interfere with one another. The trough 9 may be designed as a mud separator.

In the constructional form shown in Fig. 1 the small trough 9 resembles somewhat a semi-cylinder which is closed at its ends and is there 45 supported on pivots 11. One of the pivots is in the form of a hollow trunnion open to the interior of the trough, as at 11', and serves for letting the water escape, whereas the mud collects on the bottom of said trough 9. From time to time 50 this trough is turned on the pivots 11 in order to let the collected mud fall down. When the trough 2 is initially tipped into the position shown in Figure 3, the water contained therein above the ashes or other refuse will flow over the forward 55

edge of the trough into the smaller trough 9, and if desired the trough 2 may be retained in this position until a practically complete discharge of the water has been obtained.

5 I wish it further to be understood that the positive turning of the main trough 2 can be effected also by other members, or by another arrangement and combination of parts respectively, than by the parts 5, 6, 7 and 8, which constitute merely 10 a constructional form shown by way of example. The characteristic features of the trough 2 are first of all that it can be turned in a vertical plane and at the same time shifted in a horizontal plane, the two motions taking place without interfering 15 with the discharge branch 1, as described.

I claim:

1. A device for receiving ashes and the like from a downwardly directed discharge spout and operable to discharge such ashes at one side of 20 the spout, comprising a movable container open at the upper end to receive the discharge spout when the container is in receiving position, guiding means for the container arranged substantially at right angles with respect to the spout, 25 and supporting means carried by the container and arranged approximately on a horizontal axis through the center of gravity thereof for movably cooperating with said guide, whereby the container during its movement on the guide may be 30 gradually tilted to dispose the container in discharge position wholly at one side of the spout.

2. A device for receiving ashes and the like from a vertical discharge spout, including a movable container for the ashes delivered through the spout, the upper edge of the container being arranged above the lower edge of the spout when the container is in receiving position relative to the spout, a guide for the container arranged in a plane normal to the axis of the spout and 40 beyond the body of the container, and elements supporting the container and arranged approximately on a horizontal axis through its center of gravity and movably cooperating with the guide to permit movement of the container laterally of 45 the spout and simultaneously cause tilting on its horizontal axis to move the container wholly toward one side of the spout and to a discharge position.

3. A device for receiving ashes and the like 50 from a downwardly directed discharge spout and discharging such ashes at one side of the spout, comprising a container open at the upper end to receive the discharge spout when the container is in receiving position, a guide on which the container is movable substantially horizontally, and means connecting the container and a point fixed with relation to the spout, said means compelling gradual tilting movement of the container during such horizontal movement.

60 4. A device for receiving ashes and the like from a downwardly directed discharge spout and for discharging such ashes, comprising a container open at the upper end to receive the discharge spout when the container is in normal 65 position, a guide on which the container is movable substantially horizontally, and means connecting the container and a point fixed with re-

spect to the spout, said means compelling gradual tilting movement of the container during such horizontal movement, the relation of the horizontal and tilting movements of the container disposing the container in discharge position 5 laterally of the spout at the limit of horizontal movement in one direction.

5. In combination, a downwardly directed discharge spout, a container open at its upper end, means for normally supporting the container to 10 maintain the upper open end thereof above the lower end of the discharge spout, a guide supporting the container and permitting movement of the container at right angles with respect to the spout, and a rigid element pivotally connected 15 at its ends to the container and a fixed point to compel a tilting movement of the container during its horizontal movement, the disposition of the connection being such that in the initial horizontal movement of the container the latter is 20 tilted sufficiently to avoid contact with the spout during further horizontal movement of the container.

6. In combination with a downwardly directed discharge spout, a container located below and 25 designed to receive material delivered through the spout, the upper edge of the container being normally above the lower free edge of the spout, a trackway on which the container is mounted for bodily sliding movement in a direction at substantially right angles to the spout, and a rigid element pivotally connected at its ends to the container and a fixed point to compel a tilting movement of the container during the horizontal movement thereof, the relation of the tilting and horizontal movements of the container being such 30 as to dispose the container in discharge position when at the limit of horizontal movement.

7. A construction as defined in claim 6, wherein 40 in the container is designed to receive water to a depth to close the free end of the spout when the container is in normal position and wherein a discharge receptacle is mounted at one side of the container to receive fluid discharged therefrom during the delivery of the material through the 45 spout and during the initial tilting movements of the container.

8. A construction as defined in claim 6, wherein 50 in one wall of the container is inclined to provide an inclined discharge surface when the container is in discharge position.

9. A box-like container to receive material from a spout and having an open end to underlie the spout when the container is in receiving position, a trackway extending at right angles to the spout and arranged below the same, means carried by the container for travel along said trackway, and a link pivotally connected to the container and to the trackway for compelling a tilting movement 60 of the container during its movement in either direction along the trackway, one of such tilting movements serving to dispose the container laterally of the spout and in a discharge position, the other of said movements serving to dispose the container in a receiving position with respect 65 to the spout.

MAX SCHWABACH.
